UNITED STATES PATENT OFFICE.

JAMES L. THOMAS, OF WILMINGTON, DELAWARE.

RAIL-JOINT.

1,090,175.

Specification of Letters Patent. Patented Mar. 17, 1914.

Application filed December 16, 1913. Serial No. 807,069.

To all whom it may concern:

Be it known that I, JAMES L. THOMAS, a citizen of the United States, residing at Wilmington, in the county of Newcastle and State of Delaware, have invented certain new and useful Improvements in Rail-Joints; and I do hereby declare the following to be a full, clear, and exact description of the same, reference being had to the accompanying drawings, forming part of this specification, and to the figures and letters of reference marked thereon.

This invention relates to rail joints and is designed to overcome defects found to exist in rail joints as heretofore constructed; to supply a joint of such construction that it will effectually connect the adjacent ends of the rail; permit of all necessary movements to compensate for expansion and contraction and so support and reinforce the head of the rail as to eliminate practically all danger from a rupture or breaking down of the end of the rail under extreme traffic conditions.

A further object of the invention is to effectually eliminate all danger of bolt heads or nuts being sheared off by a derailed wheel traveling along the side of the rail and to provide means whereby, when so desired, the rails may be used effectively for an electric circuit without the necessity of separate bonding means, such as is customarily employed to supplement the joint and form a path for the current around the meeting faces or edges of the parts.

Referring to the accompanying drawings,—Figure 1 is a sectional perspective view of the joint, the plane of the section being substantially in a transverse plane intersecting one of the connecting stems; Fig. 2 is a section in a horizontal plane intersecting the connecting stems and showing the top of the chair and lower portions of the joint bars; Fig. 3 is a detail section in a vertical plane through the extreme ends of the rails and a portion of the rail chair; Fig. 4 is a perspective view looking at the inner side of one of the joint bars with portions broken away and in section to show the construction and arrangement of the parts; and Fig. 5 is a perspective view of the apertured retaining bar with which the key bar co-operates for obtaining a wedging action on the connecting stems. Like letters of reference in the several figures indicate the same parts.

In said drawings, the adjacent ends of two rails are indicated at A, A, said rails being such as are ordinarily employed, save that the bolt holes in the webs are formed in position to receive stems B which are preferably formed rigid with a retaining bar C adapted to lie along one side of the rail web, and preferably of relatively small transverse dimension, but of dove-tail form, whereby it is adapted for seating in a dove-tail recess d in an inside joint bar D. The cross sectional shape of the retaining bar C and recess in the joint bar D is such that a close fit is maintained between these parts and preferably such a fit as will require the parts to be driven together longitudinally of the rail; thus, the retaining bar having been positioned, the joint bar is driven longitudinally over the same until it reaches a position where the retaining bar is entirely concealed within it, except for an enlargement or head C' at one end, against which the end of the joint bar seats, so as to prevent independent longitudinal movement of the joint bar in that direction. The ends of the stems B referred to are notched on the top and bottom sides, as shown, at b; thus forming, as it were, heads upon the said stems adapted to overlie a key bar which will be presently described.

Over the ends of stems B there is placed a retaining bar E, preferably of dove-tail shape in cross section, with apertures therethrough for the stems, and ribs or filling pieces E' between the apertures. When the said retaining bar is in place on the ends of the stems the notches in the stems and faces of the bar form slide ways along the upper and lower sides of the stems in which the two arms f of a key bar F may slide into position, so as to effectually lock the parts together. A wedging action is secured by giving the retaining bar and key bar an appropriate taper from end to end, the taper being only sufficient to make a tight fit when the parts are brought to their final seats, although, as will be presently described, provision is made whereby the key bar may be adjusted for taking up wear or for insuring a tight fit at the initial adjustment of the parts. The retaining bar and key bar together are of dove tail shape in cross section and are adapted to seat in a correspondingly shaped longitudinal recess in an outside joint bar G. In the preferred construction the key bar is normally held

adjustably in the outside joint bar G by an adjusting screw H journaled in the end of the joint bar and having threaded connection with the end of the key bar, as will be 5 readily understood from an inspection of Fig. 4.

The key bar and retaining bar together form a close fit in the dove tail recess of the joint bar, the object being to require the 10 joint bar and key bar to be driven into place in the seating of the joint, and the movement of the joint bar in one direction is preferably limited by a head E² on the retaining bar, as shown.

15 Movements of the joint bars in the opposite direction from the heads on the retaining bars are prevented by spikes of the usual character which may be driven down through the edges or ends of the joint bars, 20 but in the preferred construction illustrated, the whole joint is mounted on and seated in a rail chair K having on its under surface the usual or preferred tie engaging ribs k, and in its upper surface a recess for the rail 25 base and at each side of said seat a recess or groove L for the reception of downwardly extending flanges or projections L' on the lower outer edges of the joint bars. The 30 flanges or projections L' which seat in the grooves or recesses L afford a very wide bearing on the rail chair, and in effect broaden the rail base in addition to firmly anchoring the same against any lateral 35 movement. The spikes for holding the parts in place on the ties may extend down through both the lower flange-like portions of the joint bars and the chair so as to form an additional fastening or connecting means 40 between these parts, and while the joint itself is of such construction that it would constitute a good bond between the rail ends, the bonding effect is preferably increased by recessing or chambering the rail chair at the 45 center and locating in such chamber a flat or bowed spring bonding member M, the edges of which are sharpened or serrated for engaging the lower faces of the rail bases on opposite sides of the joint so as to establish a good electrical connection therebetween.

50 From Fig. 1 it will be observed that the inner joint bar has its upper portion cut away forming a flange receiving concavity D² below the level of the head of the rail, while the outer joint bar extends up and has 55 its upper face substantially flush with the top of the rail head; thus, a wheel traveling on the rail may take a bearing on the upper face of the outer joint bar in traveling past the ends of the rails and consequently, 60 should any defect develop in the rail ends, the entire strain of the load will be carried and the wheel guided by the joint bars themselves. The joint bars are maintained in 65 position through an anchorage to the chair which is of sufficient strength to carry any

load which may be imposed on the parts. On both sides of the rail the joint bars fit solidly under the rail head so that the latter is supported and the web protected against undue strain at the points where it is most liable to fail; i. e., in proximity to the ends of the rails and where it is perforated for the reception of the stems. 70

The openings formed in the web of the rail for the passage of the stems are made 75 of slightly greater diameter than the said stems, for the purpose of permitting the rails to expand and contract under changes in temperature and the bars for uniting the ends of the rail together with the bolts, it 80 will be noted, are all so locked together that the locking action will not be interfered with or the parts loosened in any wise by the movements of the rails in so expanding or contracting. 85

Having thus described my invention what I claim as new, and desire to secure by Letters Patent of the United States, is,—

1. In a rail joint a T-rail having an ordinary plane-faced web perforated transversely, retaining bars dove-tail in cross section separably secured to opposite sides of the web, and joint bars having dove-tail grooves in their inner faces arranged to be driven over the retaining bars, whereby the 90 retaining bar securing means are concealed and held in position. 95

2. In a rail joint, the combination with a T-rail having an ordinary plane-faced web perforated transversely, of a retaining bar 100 located on one side of said web and having securing stems thereon passing through the perforations in the web with transverse grooves in proximity to the ends of said stems, a retaining bar mounted on said ends 105 of the stems on the opposite side of the web, a longitudinally movable key bar mounted in the grooves in the stems and a joint bar having its inner face recessed to receive the retaining bar, key bar and ends of the stems. 110

3. In a rail joint, the combination with a T-rail having an ordinary plane-faced web perforated transversely, retaining bars located on opposite sides of said web, stems connecting said retaining bars through the 115 perforations in the web, and detachable fastening means interposed between one of said retaining bars and the stems, whereby the parts may be separated, and joint bars enclosing said retaining bars and stems on opposite sides of the rail, said joint bars embodying dove-tail recesses for the reception 120 of the retaining bars, whereby the joint bars are held in position to support and connect proximate ends of adjacent rails. 125

4. In a rail joint, the combination with a T-rail having an ordinary plane-faced web perforated transversely, retaining bars of dove-tail form in cross section located on opposite sides of said web, stems connecting 130

said bars through the perforations in the web, and a key bar coöperating with the stems on the outer side of one of said retaining bars, of joint bars having their inner 5 faces formed with dove-tail grooves arranged to be driven over the retaining bars, key bar and stems, substantially as described.

5. In a rail joint, the combination with a 10 rail chair having a longitudinal rail seat therein and longitudinal grooves on the outer sides of said seat, of rails having their proximate ends mounted in said seat, retaining bars located on opposite sides of the 15 rail webs and bridging the joint between the ends of the rail, said retaining bars being of dove-tail form in cross section, stems connecting said retaining bars through the rail web, and joint bars having their inner faces 20 provided with dove-tail grooves for the reception of the retaining bars and at their lower outer edges provided with flanges seating in the longitudinal grooves in the rail chair.
- 25 6. In a rail joint, the combination with the proximate ends of adjacent rails, retaining bars of dove-tail form in cross section located on opposite sides of the rail webs and bridging the joint between the rails, 30 stems connecting said connecting bars through the rail webs and heads or enlarge-

ments on the retaining bars, of joint bars having their inner faces formed with dove-tail grooves for the reception of the retaining bars, said joint bars being seated on and 35 held in place by the retaining bars with their ends in engagement with the heads or enlargements thereon for limiting relative longitudinal movement.

7. In a rail joint, the combination with 40 the rail chair having longitudinal grooves therein, rails seated on said chair with their ends in proximity, retaining bars separately secured on opposite sides of the rail web, said retaining bars being of dove-tail form 45 in cross section and joint bars having their lower edges flanged and seating in the grooves in the rail chair and their inner faces grooved longitudinally to receive and conceal the retaining bars, said retaining 50 bars serving to hold the joint bars in position, the inner joint bar having its upper edge cut away to form a wheel flange recess and the outer joint bar having its upper portion provided with a face substantially flush with the top face of the rail head, 55 substantially as described.
